UNITED STATES PATENT OFFICE.

FRED K. BLAUVELT, OF WICHITA, KANSAS, ASSIGNOR TO CLARENCE E. REED, OF WICHITA, KANSAS.

RETAINING MEANS FOR SPINDLES OF DEEP-WELL ROTARY CUTTERS.

Application filed March 15, 1927. Serial No. 175,570.

The invention concerns rotary earth boring drills and particularly means for holding the cutting unit to the bit head, said means being adapted to draw the shank of 5 said cutting unit firmly seated in place, thereby eliminating all play, and contributing to a ruggedness of the structure to sustain the great strains to which said tools are subjected.

10 In the drawings forming a part of the specification

15 Figure 1 is a part section and elevation of a bit head embodying the invention.

Fig. 2 is a plan view of the cutting unit 20 shank.

Fig. 3 is a side view of the holding means.

Fig. 4 is a vertical sectional view of said holding means.

Fig. 5 is a sectional view at a quarter turn 25 from Fig. 4.

Fig. 6 is a bottom plan view of said holding unit.

In these drawings 1 is the bit head. The cutting unit comprises a spindle 5 with a 30 rotary cutter 3 mounted thereon in any suitable manner. This unit has a shank 6^x extending up into a socket 7^x in the bit head. At the upper end of the socket there is a recess 30 in the side of the bit head and the 35 upper end of the shank extends thereinto. This upper end is provided with wings 31 with gates 32 between them forming one part of a bayonet joint, the other part of said joint being on the holding means which 40 is located in the recess. This holding means comprises an inverted cup shaped member made in sections 33, 34. The section 33 has its opposite segmental wall portions provided with internal wings or flanges 33^a, whereas the opposing wall portions of the 45 other section of the cup shaped member or collar has no interior flanges and as shown in the bottom plan view, Fig. 6, this provides gates at 34^a between the wings 33^a of the section first mentioned.

The section 34 has its opposing wall portions connected by a cross piece 34^b at their upper ends. In this cross piece is swivelled the lower reduced end of a screw threaded 50 operating member 35. This lower reduced end is riveted in place or headed at 35^a so that it may turn in the cross piece. The screw threaded part of the operating member 35 works in a screw threaded opening in 55 the top of the cup shaped member 33. At

its upper end it is provided with openings 35^b to receive an implement by which said operating member may be turned. When turned one way the operating member will raise the member or section 33 and when turned the other way it will lower said section. The cup shaped member is slabbed off at 35^d to present a straight shoulder at this point.

In the use of the holding means it is 60 placed over the projecting upper end of the shank 5^x of the unit so that its gates 34^a will register with the wings 31 and its flanges will be in line vertically with the gates 32 on said shank. It will then be 65 lowered to rest on the bottom of the recess. Its flanges will then be in a plane below the plane of the wings or flanges on the upper end of the shank. Thereupon the entire cup shaped member is given a quarter turn which 70 will cause its flanges 33^a to ride under the flanges or wings 31 on the shank. In this position the holding means has interlocked with the shank to hold it within the socket 75 in the head. A cotter pin now may be run through openings in the bit head so as to lie along the straight shoulder 35^d and thus the holding means will be retained in position 80 against rotary displacement.

Now in order to draw the shank of the 85 unit tightly within the bit head the operating member 35 is turned, and by its screw threaded connection it draws upwardly upon the main section 33 of the inverted cup shaped member. In this action the screw 90 threaded operating member finds a seat against the cross piece of the supplemental or auxiliary section of the cup shaped member. In its upward movement the main section 33 by its flanges which engage under the 95 wings of the shank draw said shank upwardly tightly into or against the bit head. It will be observed that at the junction of the spindle and shank there is desirably a base flange 11^x. This is seated in a recess 100 12^x and against the ceiling thereof and the action just described will draw the said flange into firm engagement with the said ceiling. By means of this tightener the cutting unit 105 will be held against play and the bit head will not have a hammer action upon the unit during the operation of boring the hole.

I claim as my invention:

1. In combination in an earth boring drill a bit head, a roller cutter unit comprising a 110

roller, spindle and shank, said shank having a flange and gate at its upper end, and means for drawing and holding the shank into the head, comprising a member having a flange and gate complementary to the flange and gate of the shank, said member when moved axially of the shank and then turned bringing its flange beneath that of the shank, and operating means for drawing 10 said member upwardly relative to the drill head to draw the shank firmly to its seat in the bit head, substantially as described.

2. Locking means for the shank according to claim 1 in which means are provided for 15 preventing retrograde rotary movement of the said holding member to maintain its flange beneath and engaged with the flange on the shank of the cutting unit, substantially as described.

20 3. Holding means for the shank of the cutter unit in accordance with claim 1 in which the operating means comprises a screw threaded member passing through the holding means, and a member to rest upon the bit head in which said screw threaded member is supported and to which it is swivelled, substantially as described.

4. Holding and drawing means for the shank of a cutter unit comprising a member having a flange and gate complementary to a flange and gate on the shank, a second member to rest upon the bit head, and a screw threaded operating member swivelled in said second member and passing through and in screw threaded engagement with the first member, substantially as described.

5. In combination with a bit head a rotary cutter unit having a rotary cutter, a spindle and shank, said shank being seated in said bit head, said bit head having a recess in its side, holding means in said recess having a bayonet joint connection with the upper end of the shank and means for drawing said holding member upwardly relative to the bit head in the direction of the axis of the shank to draw the shank to its seat, substantially as described.

6. Means for holding the shank of a cutter unit to a bit head, comprising a substantially inverted cup shaped member in sections, one of said sections having a screw threaded operating member swivelled therein, said section being adapted to rest upon a

part of the bit head and furnishing a support for said operating member, and another section operated by said screw threaded member and having a flange and gate to cooperate with a flange and gate on the shank, said flanges engaging when the cup shaped member is turned about the axis of the shank, and means for retaining said holding means against backward turning, substantially as described.

7. In combination a bit head having a socket, a rotary cutter unit having a shank in said socket, said head having a recess in its side into which the upper end of the shank projects, a substantially inverted cup shaped holding means in said recess formed in sections, one section being supported on the bottom of said recess, and the other section having a bayonet joint connection with the shank, an operating member swivelled to the section first mentioned and passing through and having screw threaded engagement with the other section to raise and lower the same in respect to the first section, and means for holding the said cup shaped member against backward turning when the bayonet joint is set, substantially as described.

8. In connection with the features of claim 7, a flat shoulder or seat on one section and a pin seated removably in the bit head and engaging said shoulder or seat to hold the cup shaped member against backward turning, substantially as described.

9. Holding means for the shank of a rotary cutter unit comprising an inverted cup shaped member of cylindrical form in sections, one section having segmental walls located between the segmental walls of the other section and circumferentially in line therewith, one section having a cross piece, a screw threaded operating member swivelled in said cross piece, and passing through and engaging a screw threaded opening in the other section, so that the latter may be drawn vertically in relation to the first mentioned section, said second section having a flange and gate to cooperate with a complementary flange and gate on the said other section, substantially as described.

In testimony whereof, I affix my signature.

FRED K. BLAUVELT.
